UNITED STATES PATENT OFFICE.

JOHN BLAIR, OF NEW YORK, N. Y.

FOUNTAIN-PEN.

SPECIFICATION forming part of Letters Patent No. 328,454, dated October 20, 1885.

Application filed August 27, 1885. Serial No. 175,448. (No model.)

To all whom it may concern:

Be it known that I, JOHN BLAIR, of the city of New York, county and State of New York, have invented a new and Improved 5 Fountain-Pen, of which the following specification is a full, clear, and exact description.

This invention relates to a fountain-pen of simple construction; and it consists in the various elements of improvement hereinafter 10 more fully pointed out.

In the accompanying drawings, Figure 1 is a perspective view of my improved fountain-pen; Fig. 2, a longitudinal section of the ink-reservoir; Fig. 3, a similar section through the cap; Fig. 4, a similar section through the pen-holding tip. Fig. 5 is a side view of the ink-tube; Fig. 6, a top view of the same, and Fig. 7 a side view of the wood absorbent within the ink-tube.

20 The letter *a* represents a hollow tubular handle or ink-reservoir open at one end and closed at the other end. Around its open end there is an offset for receiving a cap, *b*, which is applied when the pen is not used.

25 *e* is the pen-receiving tip. This tip is made of a piece of sheet-metal tubing open at both ends, one end being provided with the customary outwardly-projecting spring-jaws, *d*, between which and the tube the pen is clamped. 30 Within the other or rear end of the tip *c* there is introduced a soft-rubber tube, *e*, also open at both ends. This tube is rigidly secured within the tip *c*, and partially projects out of the same, as shown in Fig. 4.

35 *f* is the ink-tube, curved upward at its front end, so as to be in contact, or nearly so, with the pen. At its rear end the tube *f* is introduced into the soft-rubber tube *e*, which serves to hold it in place. The tube *f* is provided with 40 two openings, *g* *h*, at its upper end, the opening *g* being located near its center to admit air, and the opening *h* being at the front end to discharge the ink. The opening *g* is outside of reservoir *a*, so that no ink can flow into the 45 same.

Within the tube *f* there is placed a thin strip

of wood or other absorbent, *i*, that operates similar to a wick and serves to convey the ink to the pen. By pushing this strip backward or forward the flow of ink may be increased 50 or diminished.

The soft-rubber tube *e* serves a double purpose—first, it forms a tight joint between the parts *a* *c* without screw-threading such parts, and, secondly, it permits the ink-tube 55 *f* to yield so as to conform to the spring of the pen.

I am aware that fountain-pens having an ink-tube with two openings—one of which admits and the other discharges the ink—have 60 been known before my invention, such a pen being shown in Patent No. 15,417, granted to A. G. Day, July 29, 1856.

I am also aware that metallic feed pins and springs have been placed into the ink-tubes, 65 as shown in Patents No. 12,301, granted to N. A. Prince, January 23, 1855, and No. 241,215, granted to F. Holland, May 10, 1881, and I do not claim such constructions; but

I do claim as my invention—

1. The combination of reservoir *a* and tip *c* with the upwardly-curved tube *f*, provided with the air-opening *g* and the ink-opening *h*, the air-opening being located outside of reservoir *a*, substantially as and for the purpose 75 specified.

2. The combination of reservoir *a* with the tip *c*, containing rearwardly-projecting soft-rubber tube *e*, and with the ink-tube *f*, fitted into the rubber tube, substantially as specified. 80

3. The combination of reservoir *a* and tip *c* with the tube *f*, having openings *g* *h*, and containing the absorbent strip *i*, substantially as and for the purpose specified.

4. The combination of reservoir *a* with tip 85 *c*, having soft-rubber tube *e*, and with the curved ink-tube *f*, having openings *g* *h*, and strip *i*, substantially as specified.

JOHN BLAIR.
